UNITED STATES PATENT OFFICE.

MEYER STARR, OF NEW YORK, N. Y.

CHECK WRITER.

Application filed July 12, 1922. Serial No. 574,416.

To all whom it may concern:

Be it known that I, MEYER STARR, a citizen of the United States, and residing in the borough of Bronx, county of Bronx, 5 city and State of New York, have invented certain new and useful Improvements in Check Writers, of which the following is a specification.

This invention relates to check writers and has for one of its important objects the provision of a novel means by which the several cooperative elements thereof may be easily brought into predetermined selected positions prior to the operation of the device 15 whereby the so called writing of the check or other document may be easily executed as of a desired amount.

A further object of the invention is to so construct and arrange the various cooperative elements of the device as to insure its accurate and reliable operation and make possible the production of such a device which is highly compact, inexpensive to manufacture, neat in appearance and capable of withstanding prolonged use without necessitating the renewal of parts thereof.

Other objects and certain advantages of the invention will become apparent from the following description when taken in connection with the accompanying drawings in which—

Figure 1 is a plan view of the device embodying my invention.

Figure 2 is a side elevation of the device 35 as viewed from the right in Figure 1.

Figure 3 is a bottom plan view of the device.

Figure 4 is a sectional view taken on line 4—4 of Figure 5.

Figure 5 is a longitudinal sectional view taken on line 5—5 of Figure 4.

Figure 6 is a transverse sectional view taken on line 6—6 of Figure 4.

Figure 7 is a longitudinal sectional view 45 through a die plate magazine showing the position of the several die plates in the course of being moved to advanced positions.

Figure 8 is a similar view to that of Figure 7 showing the die plates further advanced.

Figure 9 is a similar view to that of Figure 8 showing the die plates in still further advanced positions.

Figure 10 is a sectional view similar to 55 that of Figure 5 illustrating the positions of

the several die plates upon the completion of the particular cycle of operation illustrated as having begun in Figure 7.

Figure 11 is a perspective view of a die plate showing particularly the upper face 60 thereof.

Figure 12 is a view similar to that of Figure 11 showing particularly the opposite face of the die plate.

Figure 13 is a plan view of the casing 65 from which the cover plate and several die plate magazines have been removed.

Figure 14 is a perspective view of a die plate magazine.

Figure 15 is a transverse sectional view 70 taken on line 15—15 of Figure 14.

Figure 16 is a fragmental sectional view of a magazine wall showing in detail a die plate retaining shim.

Figure 17 is a fragmental face view of 75 a check or other document showing perforations formed therein as a result of the operation of the device with its several die plates positioned as indicated in Figure 1.

In the drawings wherein for the purpose of illustration is shown what I at present consider the preferred form of my invention, the numeral 5 indicates a base having a portion thereof relieved or cut away as shown at 6 in order to provide an apron 7 adapted 80 to receive thereupon the check or other document which is to be operated upon. This base is adapted to receive thereupon a casing or cover 8, provided with a plurality of windows 9 above which the words "Dollars" and "Cents" are etched, stamped or otherwise formed. In direct alignment with the windows 9 there is formed a plurality of slots 10 through which suitable operating

handles, hereinafter more particularly described, are adapted to project. The apron 7 above referred to is slightly recessed as shown at 11, and is provided with groups of perforations 12 arranged in direct alignment with and adapted for the reception of 85 a plurality of plungers 13 arranged in groups corresponding to the groups of perforations 12. These plungers are provided intermediate their ends with shoulders 14 and are adapted to project through a plurality of perforations 14' formed in a guide plate 15, suitably connected to a superimposed plate 16 mounted upon the base 5 and provided with vertically disposed side members 17. In order to effectively retain 90

100

105

110

the plungers 13 in their normal or elevated positions shown in Figure 5, I have provided a spring plate 18 which is suitably connected to the superimposed plate 16 and 5 cut away as shown at 19 to form a plurality of resilient tongues 20 which are provided at their free ends with perforations 21 adapted to receive the plungers 13. It will be noted that the superimposed plate 16 is 10 provided also with a plurality of perforations 22 adapted to receive the lower or perforating ends of the plungers 13. Due to the fact that the plungers 13 are adapted 15 to operate within the perforations 14' and 22 formed in the guide plate 15 and superimposed plate 16, respectively, it will be appreciated that they under all conditions are maintained in a parallel relation and in 20 direct alignment with the perforations 12 formed in the apron 7.

To the base 5 near one end thereof there is connected a journal bar 23 which is provided at its ends with a pair of upstanding arms 24 having stub shafts or pins 25 carried thereby. Intermediate the ends of the bar 23 there are arranged a plurality of gussets 26 carrying oppositely disposed stub shafts or pins 27 similar to those indicated by the numeral 25. This journal bar is 30 adapted to support a plurality of die plate magazines 28 which are pivotally connected to the stub shafts or pins 25 and 27 carried respectively by the wings 24 and gussets 26. Each die plate magazine 28 comprises side 35 members 29, bent at their opposite edges to provide lower and upper flanges 30 and 31 respectively, which are spaced apart as shown forming longitudinally disposed slots 32 and 33. It will be noted that the side members 40 29, at corresponding ends, are provided with ears 34 having openings 35 formed therein which are adapted to receive the stub shafts or pins carried by the wings and gussets 24 and 26, respectively. Upon each of the die 45 plate magazines 28 there is arranged a guide plate 36 having its longitudinal edges bent to provide flanges 37 forming grooves or channels 38. These guide plates are cut away to provide windows 39 adapted to register with the windows 9 formed in the cover plate 8, and are also struck up as shown at 40 to provide downwardly projecting aprons 41 arranged intermediate the side members 29. The aprons thus formed are relatively rigid 50 and function as abutments for the die plates, hereinafter more particularly referred to, as they are moved from one position to another during the selective operation of the device. Each of the magazines 28 is provided with a horizontally disposed divisional wall 42 which is suitably connected to the side members 29, as shown most clearly in Figure 15. This divisional wall, it will be noted, is relatively short as compared with the total 55 length of the magazine, and is so disposed

that opposite ends thereof are spaced an appreciable distance from corresponding ends of the magazine. At what might be termed the forward end of each of the magazines there is provided a depression foot 43, which is formed with an opening 44, and provided with an abutment 45, having a notch 46 formed therein adapted for the reception of a die plate actuating member hereinafter more particularly described. The several 70 die plate magazines 28 are adapted to move slightly about their respective pivotal connections with the stub shafts or pins 25 and 27 and are guided in their movements by a plurality of vertically disposed guide pins 80 47 suitably connected with the superimposed plate 16 and provided with spiral springs 48 which are adapted to maintain the several magazines in their respective normal positions as shown in Figure 5. 85

Within each of the magazines 28 are arranged a plurality of die plates 49, 50, 51, 52, 53, 54, 55, 56, 57, 58 and 59 which are adapted to be moved in opposite directions upon each side of the divisional wall 42 during the selective operation of the device. These plates are beveled at opposite ends to provide offset edges 60 and 61 having notches 62 and 63 formed therein, adapted for the reception of transfer lugs 64 and 65, respectively. The transfer lugs 64 are suitably connected to the ends of resilient arms 66 which are formed integral with resilient arms 67, to the ends of which the transfer lugs 65 are connected. The resilient arms 67 are cut away as shown most clearly in Figure 4 to provide windows 68 adapted to register with the windows 9 and 39 formed in the cover plate 8 and guide plates 36 respectively, so that the upper face of the die 105 plates may be readily observed when they are brought into registration with the several windows. The resilient arms 67 are tapered as most clearly shown in Figure 4, but at their rear ends they are relatively 110 wide so as to snugly fit within the grooves 38 which serve to guide them while they are being reciprocated for the purpose of moving the several die plates to predetermined positions. In order to facilitate the operation of the resilient arms 66 and 67, I have provided operating handles 69 which are suitably connected to the resilient arms 66 and bent to provide depending arms 70 to which are connected tension springs 71 suitably anchored to downwardly turned ears 72 connected to the lower flanges 30 of the several magazines. By referring to Figures 7 to 10 inclusive, it may be readily appreciated that by moving the operating handle 69 against the influence of the spring 71, the die plates 49 to 52 inclusive, are moved in a given direction by reason of the engagement of the transfer lugs 65 with the die plate 52. After a predetermined movement 115 120 125 130 135

of these plates, the plate 49 is caused to move upon the plate 59 as a result of the cam action of their adjacent beveled edges 60 and 61. As the plate 49 assumes a position 5 directly above the plate 59, the plates 59 and 58 are moved downwardly to their respective positions shown in Figure 8, whereupon the transfer lug 64 snaps into position within the notch 62. After the transfer lug 10 64 enters the notch 62 the resilient arm 66 is permitted to move under the influence of the spring 71 to the position shown in Figure 10 carrying with it the several plates 58, 57, 56 and 55.

15 As a result of such movement the plate 55 is caused to move under the plate 54 and lift the same, together with the plate 53, to their respective positions shown in Figure 10. By continued operation of the operating handle 20 69 the series of die plates may be caused to continue their transferal from one end of the magazine to the other, thus enabling any one of said plates to assume a desired position in the course of its travel. In order to prevent undue displacement of the die plates 25 which are about to be transferred from one plane to the other, at the ends of the magazine I have provided resilient shims 73 and 74, the opposite ends of which are adapted to enter notches 75 recessed in the walls 29 of the magazine, as clearly shown in Figure 16. And to prevent undue longitudinal displacement of the die plate resting in parallel planes at opposite sides of the divisional wall 42, I have provided a pair of shims 76 and 77 which are similarly held in position upon opposite sides of the divisional wall.

30 The die plates above referred to are provided, upon their upper faces, with etched or otherwise relieved indicia indicated by the numeral 78 and at their opposite sides are provided with embossed outlines indicated by the numeral 79 which stand out flush 35 or substantially flush with ribs 79' provided at opposite ends of the plates in order to facilitate their travel and assist in maintaining the same correctly positioned within the magazines. It might be remarked, however, 40 that in no instance does the same numeral or indicia appear upon opposite faces of a given die plate since the embossed outline is so positioned as to cooperate with the plungers 13 when a corresponding indicia is so positioned as to be observed through the windows 9. These indicia may include numerals, abbreviations, symbols or such other characters as may be desired in a particular device but in the embodiment of the device 45 herein shown I make use of only numerals in combination with the symbol known as the dollar mark which combination enables me to express a maximum amount of \$9999.99. If it is desired however to denote a denomination in the absence of a prefixed dollar 50 mark I am enabled to indicate the maximum amount of 99999.99. It will be appreciated that the amount which I am enabled to indicate by the use of the device embodying my invention is limited only by the number 55 of die plate magazines 28 employed in the device, that is to say the amount which I am enabled to indicate with the device herein shown may be increased by adding additional magazines to the left of those already shown in Figure 4.

60 In order to progressively actuate the several magazines I have provided a rotatable shaft 80 journaled at one end in one of the side members 17, the other end thereof being adapted to enter a slot 81 formed in the opposite side member 17. For the purpose of retaining the shaft 80 in position within its bearings, I employ a latch lever 82 pivotally connected to one of the side members 17. 65 The shaft 80 is formed with an extension 83 adapted to project through one of the side members of the cover 8. To the extension 83 there is suitably connected a hinge plate 84 to which is hingedly connected an operating handle 85 adapted to be folded when not in use from its full line position shown in Figure 2 to its dotted line position shown in Figure 1. To the shaft 80 there is suitably connected a plurality of lugs or pins 86 70 which are spirally arranged as shown most clearly in Figure 4. These pins are adapted to coact with the depression feet 43 and so move them against the influence of the springs 48 as to cause a slight depression or 75 bodily movement of the magazines 28 about their respective pivots. By rotating the shaft 80 and thus causing a progressive depression of the magazines 28, the die plates which are positioned directly over the 80 group of plungers 13 cause a corresponding depression of predetermined or selected plungers; that is to say if a die plate carrying for example the embossed numeral "3," is positioned as shown in Figures 5 and 10, the plungers 13 which are engaged by the embossed or raised character will be depressed and forced through a check or other document 87, inserted between the base 5 and the superimposed plate 6, thus producing 110 a series of perforations corresponding to the contour of the numeral "3." The remaining plungers 13 which are positioned directly below the die plate carrying such a numeral will not be acted upon by the die plate due to the presence of the relieved area 88 surrounding the embossed numeral. It will be appreciated therefore that if the die plates of the several magazines shown in Figure 4 are so positioned that the indicia \$2705.12 appears through the windows 9, the die plates which are positioned over the several groups of plungers 13 will present on their lower faces embossed characters corresponding to \$2705.13 and that by rotating 115 120 125 130

the shaft 80 while a check or other document is inserted the same will be so perforated as to indicate the amount shown in Figure 17 namely, "\$2705.13." By properly operating the several handles 69 any desired combination of numerals or characters may be brought into selected positions to facilitate the writing of any desired amount ranging from zero up, the maximum amount being limited only by the number of magazines employed as above explained.

In order to provide for the perforation of a decimal point intermediate the units of dollars and tens of cents positions I employ a single or individual punch 88' which is identical with the several punches hereinbefore described. This punch is adapted to be retained in its normal position by a wing 89 carried by one of the resilient tongues 20 and is adapted to be depressed by a cooperating ear 90 carried by one of the magazines 28. At the right of the units of cents position it may be desirable to provide a group of perforations 91 for ornamental or other purposes and to this end I employ a plurality of punches 92 which project through a wing 93 carried by one of the resilient tongues 20 and are acted upon by a cooperating ear 94 carried by the magazine arranged at the extreme right as shown in Figure 4 the operation of which is the same as that of the ear 90 above described.

While I have shown and described my invention as embodied in a check writer it is to be understood that the same is not necessarily limited to such a device inasmuch as various changes in the size, shape, arrangement, and number of elements may be resorted to without departing from the spirit of the invention set forth in the subjoined claims.

I claim:

1. A check writer comprising a magazine, a plurality of die plates carried within said magazine and arranged in different planes, means for moving said plates in their respective planes and for transferring them from one plane to the other, and perforating means adapted to cooperate a given plate for carrying out a perforating operation.

2. A check writer comprising a magazine, a plurality of die plates carried within said magazine and arranged in different planes, means for moving said plates longitudinally in opposite directions within their respective planes and for bodily transferring said plates successively from one plane to the other, and perforating means adapted to cooperate with a given plate for carrying out a perforating operation.

3. A check writer comprising a plurality of magazines, a plurality of die plates carried within each of said magazines and arranged therein in different planes, means for moving said plates within their respective

magazines in their respective planes and for transferring them from one plane to the other, and perforating means adapted to cooperate with a given plate of each magazine for carrying out a series of perforating operations.

4. A check writer comprising a plurality of magazines, a plurality of die plates carried within each of said magazines and arranged therein in different planes, means for moving said plates within said magazines in their respective planes and for transferring them from one plane to the other, perforating means adapted to cooperate with a given plate of each magazine, and means adapted to be so operated as to effect a series of successive perforating operations.

5. A check writer comprising a magazine, pivot means at one end of said magazine, a plurality of die plates carried within said magazine and arranged in different planes, means for moving said plates in their respective planes and for transferring them from one plane to the other, perforating means adapted to cooperate with a given plate for carrying out a perforating operation, and means for so moving said magazine about said pivot means as to facilitate said perforating operation.

6. A check writer comprising a magazine, a plurality of die plates carried within said magazine and arranged in different planes, operable means adapted to move the plates of one plane in a given direction and for moving the plates of the other plane in an opposite direction, means for facilitating a transfer of plates from one plane to the other, and perforating means adapted to cooperate with a given plate for carrying out a perforating operation.

7. A check writer comprising a magazine, a plurality of die plates carried within said magazine and arranged in different planes, operable means adapted to move the plates of one plane in a given direction and for moving the plates of the other plane in an opposite direction, means for facilitating a transfer of plates from one plane to the other, perforating means adapted to cooperate with a given plate for carrying out a perforating operation, and means cooperating with said perforating means for facilitating said perforating operation.

8. A check writer comprising a magazine, a plurality of die plates carried within said magazine and arranged in different planes, means for moving said plates in their respective planes and for transferring them from one plane to the other, means for normally restraining said plates against movement within their respective planes, and perforating means adapted to cooperate with a given plate for carrying out a perforating operation.

9. A check writer comprising a magazine,

- a plurality of die plates carried within said magazine and arranged in different planes, means for moving said plates in their respective planes and for transferring them from one plane to the other, means for normally restraining said plates against movement within their respective planes, means for normally restraining said plates against transferal from one plane to the other, and 5 perforating means adapted to cooperate with a given plate for carrying out a perforating operation.
10. A check writer comprising a magazine, a plurality of die plates carried within said magazine and arranged in different planes, means for moving said plates in their respective planes and for transferring them from one plane to the other, means for normally restraining said plates against 15 movement within their respective planes, perforating means adapted to cooperate with a given plate for carrying out a perforating operation, and means adapted to cooperate with said perforating means for facilitating said perforating operation.
11. A check writer comprising a magazine, a plurality of die plates carried within said magazine and arranged in different planes, means for moving said plates in 20 their respective planes and for transferring them from one plane to the other, means for normally restraining said plates against movement within their respective planes, means for normally restraining said plates against 25 transferal from one plane to the other, perforating means adapted to cooperate with a given plate for carrying out a perforating operation, and means adapted to cooperate with said perforating means for facilitating said perforating operation.
12. A check writer comprising a base, a plurality of magazines pivotally connected to said base, a plurality of die plates carried within each of said magazines and arranged in different planes, means for moving said plates in their respective planes and for transferring them from one plane to the other, perforating means adapted to cooperate with a given plate of each magazine, and operative means adapted to be so actuated as to move said magazines about 40 their respective pivots whereby given plates of said magazines are caused to progressively cooperate with said perforating means to facilitate the carrying out of a series of succeeding perforating operations.
13. A check writer comprising a magazine, a plurality of die plates carried within said magazine and arranged in different planes, said die plates being provided with raised and depressed areas, means for moving said plates in their respective planes and for transferring them from one plane to the other, a plurality of punches, and 45 means for so moving said magazine as to cause the raised area of a given plate to engage and depress a given series of punches.
14. A check writer comprising a magazine, a plurality of die plates carried within said magazine and arranged in different planes, said die plates being provided with raised and depressed areas, means for moving said plates in their respective planes and for transferring them from one plane to the other, a plurality of punches, means for so moving said magazine as to cause the raised area of a given plate to engage and depress a given series of punches, and means for returning said magazine to its 50 normal position after the depressing of said punches.
15. A check writer comprising a magazine, a plurality of die plates carried within said magazine and arranged in different planes, said die plates being provided with raised and depressed areas, means for moving said plates in their respective planes and for transferring them from one plane to the other, a plurality of punches, means for so moving said magazine as to cause the raised area of a given plate to engage and depress a given series of punches, means for returning said magazine to its normal 55 position after the depressing of said punches, and means for returning said punches to their normal positions upon the return of said magazine to its normal position.
16. A check writer comprising a magazine having side walls, a divisional wall arranged intermediate said side walls, a plurality of die plates carried within said magazine and arranged in parallel planes upon opposite sides of said divisional wall, means for moving said plates in their respective planes and for transferring them from one plane to the other, and perforating means adapted to cooperate with a given plate for carrying out a perforating operation.
17. A check writer comprising a magazine having side walls, a divisional wall arranged intermediate said side walls, a plurality of die plates carried within said magazine and arranged in parallel planes upon opposite sides of said divisional wall, means for moving said plates in their respective planes and for transferring them from one plane to the other, perforating means adapted to cooperate with a given plate for carrying out a perforating operation, and means adapted to cooperate with said perforating means for facilitating the carrying out of said perforating operations.
18. A check writer comprising a magazine, a plurality of die plates carried within said magazine and arranged in different planes, said die plates being provided with

cam faces, means for moving the plates of one plane in a given direction and for moving the plates of the other plane in an opposite direction, said plates being so cammed as a result of the coaction between their respective cam faces as to facilitate the transferal of plates from one plane to the other, and perforating means adapted to cooperate with a given plate for carrying out a perforating operation.

19. A check writer comprising a magazine, a plurality of die plates carried within said magazine and arranged in different planes, said die plates being provided with cam faces, means for moving the plates of one plane in a given direction and for moving the plates of the other plane in an opposite direction, said plates being so cammed as a result of coaction between their respective cam faces as to facilitate the transferal of plates from one plane to the other, perforating means adapted to cooperate with a given plate for carrying out a perforating operation, and means cooperating with said perforating means for facilitating the carrying out of said perforating operation.

20. A check writer comprising a movable magazine having side walls, a divisional wall arranged intermediate said side walls, a plurality of die plates carried within said magazine and arranged in parallel planes upon opposite sides of said divisional wall, means for moving said plates in their respective planes and for transferring them from one side of said divisional wall to the other side thereof, a depression foot associated with said magazine, resilient means cooperating with said foot to retain said magazine in a normal position, perforating means adapted to cooperate with a given plate for carrying out a perforating operation, and operable means adapted to so cooperate with said foot as to move said magazine to facilitate cooperation between said perforating means and a given plate whereby a perforating operation is effected.

21. A check writer comprising a movable magazine having side walls, a divisional wall arranged intermediate said side walls, a plurality of die plates carried within said magazine and arranged in parallel planes upon opposite sides of said divisional wall, means for moving said plates in their respective planes upon opposite sides of said divisional wall and for transferring them from one plane to the other, a plurality of punching elements adapted to cooperate with a given plate for carrying out a perforating operation, and means for so moving said magazine as to facilitate cooperation between said punching elements and a given plate whereby a perforating operation is effected.

22. A check writer comprising a movable magazine having side walls, a divisional wall

arranged intermediate said side walls, a plurality of die plates carried within said magazine and arranged in parallel planes upon opposite sides of said divisional wall, means for moving said plates in their respective planes upon opposite sides of said divisional wall and for transferring them from one plane to the other, a plurality of punching elements adapted to cooperate with a given plate for carrying out a perforating operation, means for so moving said magazine as to facilitate cooperation between said punching elements and a given plate whereby a perforating operation is effected, and spring tension means adapted to return said magazine to its normal position upon the completion of said perforating operation.

23. A check writer comprising a movable magazine having side walls, a divisional wall arranged intermediate said side walls, a plurality of die plates arranged in an end to end relation upon opposite sides of said divisional wall, means for longitudinally moving the die plates upon one side of said divisional wall, means for moving the die plates upon the opposite side of said divisional wall in an opposite direction, means effecting the transferal of die plates from one side of said wall to the other side thereof, a plurality of perforating elements adapted to be depressed, means for so moving said magazine as to effect a cooperation between a given die plate and said perforating elements whereby the perforating elements of a selected group are depressed, means for returning said magazine to its normal position, and means for returning said perforating elements to their respective normal positions upon the return of said magazine to its normal position.

24. A check writer comprising a magazine, a plurality of die plates carried within said magazine and arranged in different planes, said die plates being provided upon opposite sides with unlike indicia, means for moving said plates in their respective planes, and for transferring them from one plane to the other, a casing enclosing said magazine, said casing being provided with an opening whereby the indicia upon one side of a given plate may be observed to determine the position of another plate having similar indicia upon its obverse side, and perforating means adapted to cooperate with a given plate for carrying out a perforating operation.

25. A check writer comprising a movable magazine, a plurality of die plates carried within said magazine and arranged in different planes, said die plates being provided upon opposite sides with unlike indicia, means for moving said plates in their respective planes and for transferring them from one plane to the other, a casing enclos-

ing said magazine, said casing being provided with an opening whereby the indicia upon one side of a given plate may be observed to determine the position of another plate 5 having similar indicia upon its obverse side, perforating means adapted to cooperate with a given plate for carrying out a perforating operation, means for so moving said magazine as to facilitate the cooperation 10 between said perforating means and a given plate whereby said perforating operation is effected.

26. A character forming device comprising a magazine, a plurality of character forming units carried within said magazine and arranged in different planes, means for moving said units in their respective planes and for transferring them from one plane to the other, and character forming means 20 adapted to cooperate with a given unit for carrying out a character forming operation.

27. A character forming device comprising a magazine, a plurality of character forming units carried within said magazine and arranged in different planes, means for moving said units in their respective planes and for transferring them from one plane to the other, means for normally restraining said units against movement within 25 their respective planes, and indicia forming means adapted to cooperate with a given unit for carrying out a character forming operation.

28. A character forming device comprising a magazine, a plurality of character forming units carried within said magazine and arranged in different planes, means for moving said units in their respective planes and for transferring them from one plane to the 30 other, means for normally restraining said units against movement within their respective planes, means for normally restraining said units against transferal from one plane to the other, and character forming means adapted to cooperate with a given unit in carrying out a character forming 35 operation.

29. A character forming device comprising a magazine, a plurality of movable mag-

azines, a plurality of character forming units carried within each of said magazines and arranged in different planes, means for moving said units in their respective planes and for transferring them from one plane to the other, character forming means adapted 50 to cooperate with a given unit of each magazine, operative means adapted to be so actuated as to effect a movement of said magazines whereby given units of said magazines are caused to progressively cooperate 55 with said character forming means to facilitate the carrying out of a series of succeeding character forming operations.

30. A character forming device comprising a magazine, a plurality of character forming units carried within said magazine, said units being adapted to travel in different planes and to move from one plane into the other, means for moving said units in their respective planes and for transferring them from one plane into the other, and character forming means adapted to cooperate with a given unit for carrying out a 60 character forming operation.

31. A character forming device comprising a magazine, a plurality of character forming units carried within said magazine and arranged in different planes, said character forming units being provided with cam faces, and means for cooperating with 65 said character forming units to effect a coaction between their respective cam faces whereby the units are transferred from one plane into the other.

32. A character forming device comprising a magazine, a plurality of character forming units carried within said magazine, and arranged in different planes, said units being provided with cam faces, and means for moving said units in their respective 70 planes, and for effecting a coaction between the cam faces of said units whereby the units are transferred successively from one plane into the other.

In testimony whereof, I have affixed my 75 signature to this specification.

MEYER STARR.
